UNITED STATES PATENT OFFICE.

DOLPH LEE STRINE, OF WINTERHAVEN, FLORIDA.

ADJUSTABLE PLUNGER.

Application filed December 3, 1921. Serial No. 519,601.

To all whom it may concern:

Be it known that I, DOLPH LEE STRINE, a citizen of the United States of America, residing at Winterhaven, in the county of Polk and State of Florida, have invented certain new and useful Improvements in Adjustable Plungers, of which the following is a specification.

This invention relates to pumps and has special reference to a piston or plunger for pumps of the reciprocating piston type.

One important object of the invention is to improve the general construction of pump pistons.

15 It is a well understood fact that the cylinder walls of pumps, especially such pumps as are used for spraying and other purposes where the piston must fit tightly to obtain the necessary pressure, become rapidly worn.

20 Consequently the piston no longer fits properly and leaks.

A second important object of the invention is to provide an improved form of piston for pumps of this character which 25 may be expanded from time to time to compensate for wear on the pump cylinder.

In the wear of pump cylinders the enlargement of the cylinder due to such wear takes place at that part which is rubbed by the 30 piston in its reciprocation. The piston does not reciprocate under ordinary conditions throughout the entire length of the pump but there is a space at each end which is not rubbed by such piston. Consequently 35 any piston which requires withdrawal from the pump cylinder for the purpose of expansion or which cannot be put into the pump cylinder in a collapsed condition and then expanded is ineffective to take up the 40 wear.

A third very important object of the invention is to provide an improved form of piston which may be expanded after insertion sufficiently into the pump cylinder to 45 bring the cylinder wall contacting part of the piston within the worn part of the cylinder barrel.

A fourth important object of the invention is to provide means for the above portion 50 which may readily be operated by hand without requiring any tools whatever.

With the above and other objects in view, the invention consists in general of certain novel details of construction and combinations of parts hereinafter fully described,

illustrated in the accompanying drawings, and specifically claimed.

In the accompanying drawings, like characters of reference indicate like parts in the several views, and:—

Figure 1 is a side elevation of the improved pump piston removed from the pump.

Figure 2 is a vertical median section therethrough.

Figure 3 is a bottom plan view of the piston.

Figure 4 is a detail elevation of the lower part of the piston with the cup packings shown in the foregoing figures removed.

Figure 5 is a detail section of a small part of the improved piston showing a modification of certain elements thereof.

In the embodiment of the invention herein illustrated there is provided a screw 10 having on its upper end a fork 11 through the arms of which passes a pivot pin or bolt 12. This pivot pin or bolt also passes through the pump rod 13 so that such rod is permitted to oscillate with reference to the screw 10 while the screw cannot rotate on its axis with respect to the rod 13. Since the rod 13 is held from rotation by its connection with the operating mechanism of the pump in the usual manner the screw will be also held from such rotation. The piston consists of a main portion which comprises a hollow cylindrical body 14 threaded at its lower end as at 15 and in this threaded portion is screwed a plug 16 having a screw threaded opening therein so that the body 14 and plug 16 can be screwed together onto the screw 10. Surrounding the opening in the plug 16 is a recess 17 wherein is carried a packing washer 18 to prevent leakage of fluid along the threads of the screw. On the screw 10 in spaced relation to the piston body is mounted a disk 19 which is of slightly less diameter than the shell 14 and on top of this disk is a cup packing 20 which is preferably made of leather or the like in the usual way. It will be noted from Figure 2 that the shell 14 and plug 16 have their lower ends beveled off as at 21 and the extremity of this beveled portion extends downward through the cup packing 20. The disk 19, after it is screwed into position, is held against accidental rotation by a suitable cotter pin 22 or other like device, the disk being slotted as at 23 at diametrically

opposite points for the reception of the head of this pin.

It will now be obvious that rotation of the body of the piston to move the same down along the screw will have the effect of forcing the side walls of the cup packing outward while rotation of the body in the opposite direction will permit collapse of said side walls. Beneath the disk 19 is mounted a second cup packing 24 and in the hollow portion of this cup packing is a nut 25 of inverted frusto-conical form, the nut being held in position on the screw by a suitable pin 26. Owing to the form of this nut whenever the piston moves downward the fluid being pumped enters the space between the nut and the wall of the cup packing 20 and expands the latter automatically.

In the form of the device shown in Figure 5 the plug 16 has no beveled portion 21 as the bevel portion of the shell 14 extends downward to the bottom of the plug 16, the plug being simply screwed into the shell 14 and not having any shoulder as shown in Figure 2.

In operation the lower end of the piston is inserted in the pump cylinder, the plug 16 having been screwed up on the screw 10 as far as it will go. After the cup packings 20 and 24 have reached a position sufficiently far within the cylinder to bring them opposite the part of such cylinder as is contacted by these packings in operation, the part 14 will project and this part is grasped by the hand and rotated to force it downward into the cup packing 20 thus expanding the walls of that packing until they fit the cylinder to the required degree of pressure. The pump may then be operated in the usual way. As the cylinder walls wear or as the packing wears the piston is withdrawn sufficiently far to enable the part 14 to be grasped by the hand and this part is rotated to force it further into the cup 20. In case the cup or cylinder 20 becomes so badly worn that the cup will not, even when fully expanded, properly engage the cylinder wall the body of the piston is run up on the screw and the entire piston withdrawn. The cup packings may then be removed by first removing the nut 25, taking up the lower cup packing, removing the disk 19 and then removing the upper cup packing 20. New cup packings may then be placed in position and the device inserted in the cylinder and then expanded in the usual manner.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is

wished to include all such as properly come within the scope claimed.

Having thus described the invention, what is claimed as new, is:—

1. In a pump piston, a stem, a body mounted on said stem, and a cup packing mounted on said stem, said stem and body being provided with coacting adjusting means operable by relative rotative movement of the stem and body and arranged to force the cup packing to expand.

2. A pump piston including a threaded stem, a piston body screwed on said stem and rotatable thereon to move longitudinally thereof, said body having a tapered end, and a cup packing mounted in fixed position on said stem, the hollow portion of said cup packing receiving the tapered end of the body whereby rotation of the body on the stem in one direction will force said tapered end into the cup packing and thereby expand the same.

3. A pump piston comprising a threaded stem, a piston body including an outer shell and a plug screwed onto said stem and into the lower end of the outer shell, said body having its lower end of inverted frusto-conical form, a cup packing mounted on said threaded stem and having its hollow portion toward the body, the tapered end of said body entering said hollow portion, and a disk threaded on said stem below said packing to hold the latter against downward movement on the stem.

4. A pump piston comprising a threaded stem, a piston body including an outer shell and a plug screwed onto said stem and into the lower end of the outer shell, said body having its lower end of inverted frusto-conical form, a cup packing mounted on said threaded stem and having its hollow portion toward the body, the tapered end of said body entering said hollow portion, and a disk threaded on said stem below said packing to hold the latter against downward movement of the stem, a second cup packing mounted on said stem below the disk and facing in the opposite direction to the first cup packing, and a nut screwed on said stem within the second cup packing.

5. A pump piston comprising a threaded stem, a piston body including an outer shell and a plug screwed onto said stem and into the lower end of the outer shell, said body having its lower end of inverted frusto-conical form, a cup packing mounted on said threaded stem and having its hollow portion toward the body, the tapered end of said body entering said hollow portion, and a disk threaded on said stem below said packing to hold the latter against downward movement of the stem, a second cup packing mounted on said stem below the disk and facing in the opposite direction to the first cup packing, and a nut screwed on said stem within the second cup packing.

on said stem within the second cup packing, said nut being of inverted frusto-conical form whereby to provide a channel of triangular cross section between the nut and the side wall of the second cup packing.

6. A pump piston including a threaded stem, a piston body screwed on said stem and rotatable thereon to move longitudinally thereof, said body having its lower end reduced, and a cup packing mounted in fixed position on said stem, the hollow portion of said cup packing receiving the reduced end of the body whereby rotation of the body on the stem in one direction will force said reduced end into the cup packing and thereby expand the same.

7. A pump piston comprising a threaded

stem, a piston body including an outer shell screwed onto said stem and having its lower end reduced, a cup packing mounted on the projecting portion of the threaded stem and having its hollow portion toward the shell, the reduced end of said shell entering said hollow portion a disk threaded on said stem below said packing, a second cup packing mounted on said stem below the disk and facing in the opposite direction to the first cup, and a nut screwed on said stem within the second cup packing and arranged to provide a channel between said nut and the inner side wall of the second cup packing.

In testimony whereof I affix my signature.

DOLPH LEE STRINE.
